UNITED STATES PATENT OFFICE.

MAGNE FORDE, OF OSAGE, IOWA.

DESIGN FOR A BADGE.

SPECIFICATION forming part of Design No. 33,322, dated October 9, 1900.

Application filed August 29, 1900. Serial No. 28,481. Term of patent 7 years.

To all whom it may concern:

Be it known that I, MAGNE FORDE, a citizen of the United States, residing at Osage, in the county of Mitchell and State of Iowa, 5 have invented and produced a new and original Design for Badges, of which the following is a specification, reference being had to the accompanying drawings, which show, in—

Figure 1, a plan view of my badge, and in 10 Fig. 2 an edge view of the same.

As shown, the leading or material feature of my design consists of the representation or 15 figure of two specimens of the flower known as the "ox-eye daisy," the same being arranged side by side and in the same plane and the leaves on their adjacent or inner sides being interlocked.

Another feature of my design is the bust 20 pictures, which represent William McKinley and Theodore Roosevelt, the present president-

tial and vice-presidential candidates, respectively, of the Republican party, the same occupying the centers or "eyes" of the daisies.

Another feature of my design is the arrangement of a curved or irregular flat scroll, the 25 same joining the edges of the leaves of the two daisies on the lower side.

Having described my invention, what I claim as new, and desire to secure by Letters Patent, is—

The design for a badge substantially as shown and described.

In testimony whereof I have signed my name to this specification in the presence of two subscribing witnesses.

MAGNE FORDE.
